The ornamental design for a spool mount for clippers on a rotating table, as shown and described.

DESCRIPTION

FIG. 1 is a top, rear end perspective view of the spool mount for clippers on a rotating table showing our design (the bottom view is disclaimed);

FIG. 2 is a top, opposing front end perspective view thereof; FIG. 3 is a side view thereof, the opposing side view being the same;

FIG. 4 is a front end view thereof;

FIG. 5 is a top view thereof;

FIG. 6 is a rear end view thereof; and,

FIG. 7 is an exemplary environmental view illustrating the spool mount in an exemplary position on a rotating table and holding spools of clips to feed clips to a clipper.

The broken lines shown herein are for illustrative purposes only and form no part of the claimed design.
